DESIGN FOR A COMBINED BOTTLE AND CAP

Raoul E. Hankar, Scarsdale, N. Y., assignor to
L. T. Piver, Inc., Wilmington, Del., a corpora-
tion of Delaware

Application September 18, 1935, Serial No. 58,611

Term of patent 14 years

To all whom it may concern:

Be it known that I, Raoul E. Hankar, a citizen of the United States, residing in Scarsdale, county of Westchester, and State of New York, have invented a new, original, and ornamental Design for a Combined Bottle and Cap, of which the following is a specification, reference being had to the accompanying drawing, forming a part thereof.

In the drawing:—

Fig. 1 is a perspective view of the combined bottle and cap showing my new design.

Fig. 2 is a side view; and

Fig. 3 is a bottom view thereof.

I claim:

The ornamental design for a combined bottle and cap substantially as shown.

RAOUL E. HANKAR.
